ANTENNA ROTATOR REMOTE CONTROL HOUSING

Jean O. Reinecke, Chicago, Ill., assignor, by mesne assignments, to The Alliance Manufacturing Company, Newark, Ohio, a corporation of Ohio

Application May 11, 1953, Serial No. 24,957

Term of patent 14 years

(Cl. D26—14)

FIG. 1

FIG. 2

FIG. 3

FIG. 4

FIG. 5

To all whom it may concern:

Be it known that I, Jean O. Reinecke, a citizen of the United States, in the city of Chicago, county of Cook, and State of Illinois, have invented a new, original, and ornamental Design for an Antenna Rotator Remote Control Housing, of which the following is a specification, reference being had to the accompanying drawings forming a part hereof.

Figure 1 is a top plan view of an antenna rotator remote control housing showing my new design;

Figure 2 is a rear elevational view;

Figure 3 is a front elevational view thereof;

Figure 4 is a side elevational view looking at the right end thereof as viewed in Figure 2; and

Figure 5 is a perspective view as viewed from a point above and to the right of the front of the housing.

I claim:

The ornamental design for an antenna rotator remote control housing, substantially as shown.
